UNITED STATES PATENT OFFICE.

WILLIAM M. AMMERMAN, OF NEW HAVEN, CONNECTICUT, ASSIGNOR TO THE EDWIN J. TOOF COMPANY, OF NEW HAVEN, CONNECTICUT, A CORPORATION OF NEW JERSEY.

TAKE-UP FOR SEWING-MACHINES.

No. 842,161.

Specification of Letters Patent.

Patented Jan. 29, 1907.

Application filed May 4, 1904. Serial No. 206,291.

To all whom it may concern.

Be it known that I, WILLIAM M. AMMERMAN, a citizen of the United States, and a resident of New Haven, in the county of New Haven and State of Connecticut, have invented certain new and useful Improvements in Take-Ups for Sewing-Machines, of which the following is a specification.

This invention relates to improvements in sewing-machine take-ups, and more particularly to that class of take-ups in which a take-up lever is pivotally connected at one end to a rotary actuating-crank and is fulcrumed at a point between its ends on the free end of a link that is pivotally attached at its opposite end to some stationary part of the frame of the machine, such arrangement and combination of parts causing combined translatory and vibrating movements to be imparted to the take-up lever when the machine is in operation. In adjusting the take-up for coöperation with the other parts of the stitch-forming mechanism great accuracy is required in order to assure perfect stitching; and it has therefore been one of the objects of my present invention to provide an improved take-up mechanism having adjusting means whereby the throw or movement of the take-up lever may be conveniently and accurately adjusted after the several parts of the mechanism have been otherwise assembled. This object I attain by means of the novel features of construction and combination of parts, as hereinafter set forth in detail, and pointed out in the claims.

Referring to the accompanying drawings, forming part of this specification, Figure 1 is a front end elevation, with the face-plate removed, of a sewing-machine arm provided with my improved take-up. Fig. 2 is a side elevation of the same with the arm broken away. Figs. 3 and 4 are detail views illustrating the take-up and certain associated parts at different times during the operation of the machine. Figs. 5 and 6 are end and side views, respectively, of an adjustable pivot-support detached from the crank-disk; and Figs. 7 and 8 are edge and side views, respectively, of the crank-disk. Similar reference characters designate like parts in all the figures of the drawings.

The sewing-machine herein shown, to which I have applied my improved take-up, comprises the arm or frame 1, the rotating driving-shaft 2, mounted in suitable bearings in said arm or frame and carrying at the front end thereof a crank-disk 3, and the reciprocating needle-bar 4, connected with and actuated by said crank-disk 3 through the medium of a pitman 5. These parts are of usual construction and operation. The take-up embodying my invention, as herein shown, comprises the straight or substantially straight take-up lever 6, pivotally connected at one end to the said crank-disk 3 and fulcrumed at a point between its ends at 7 to the free end of a swinging link 8, that is pivotally attached at its opposite end to the arm of the machine at 9. With the parts constructed and arranged as thus described and as shown the crank 3 and the link 8 will so operate the take-up lever as to cause its free or thread-engaging end to coöperate with the other parts of the stitch-forming mechanism in a desired manner to properly control the thread during the stitch-forming operation.

The crank-disk 3 is provided with the usual crank-pin for the connection therewith of the needle-bar pitman 5. This crank-pin (indicated at 10) is also utilized for effecting connection between the take-up lever and the said crank-disk; but in the present case instead of making a direct connection between the take-up lever and the crank-pin by entering the latter into an opening in the lever in the usual manner the said crank-pin is provided at the front end thereof with an eccentrically-located pivot, herein shown as a screw 11, for connection with the take-up lever. With this arrangement of parts by turning the pin 10 in its seat 12 in the crank-disk the position of the supported pivot 11 may be shifted to adjust the throw or movement of the connected take-up lever within certain limits, and thereby permit a desired accuracy of coöperation of the take-up with the other parts of the stitch-forming mechanism to be obtained. Any suitable means may be employed to secure the pin 10 in adjusted position within its seat, the means provided for such purpose, as herein shown,

being a clamping or set screw 14, engaging with the disk at opposite sides of a slit 15 therein, which intersects the said pin-seat and causing the walls of the latter to clamp 5 and hold the contained pin in adjusted position.

As a means for permitting adjustment of the take-up without removing or disassembling any of the parts thereof the arm or 10 frame 1 is provided with an opening 16 in a position opposite the peripheral edge of the crank-disk, as shown in Fig. 2, through which a screw-driver or other suitable tool may be inserted for the purpose of operating 15 the clamping-screw 14, it being understood that by loosening the said screw to unclamp the pivot-supporting pin 10 the latter may be turned to shift or adjust the position of the pivot 11 as desired by means of the take-up lever, after which the parts will be secured in adjusted position by again tightening the 20 said clamping-screw.

The take-up lever 6 is provided with the usual thread-receiving eye 6' at its outer end, 25 having a threading-slit 6" for the entrance of the thread thereinto, which said slit is normally closed by a spring 17, that is so arranged as to permit the ready passage of the thread past the same into the eye 6' and 30 thereafter prevent the accidental withdrawal of the thread from said eye.

What I claim is—

1. A sewing-machine take-up mechanism, comprising a rotary crank, a take-up lever 35 pivotally connected at one end to said crank, means for adjusting said take-up lever bodily in a direction radially relative to the axis of said crank, and means coöperating with said crank for controlling the movement of said 40 take-up lever.

2. A sewing-machine take-up mechanism, comprising a rotary crank, a take-up lever, a pivot carried by said crank to which one end of said take-up lever is connected and being 45 adjustable to adjust the take-up lever bodily in a direction radially relative to the axis of

the crank, and means coöperating with said crank for controlling the movement of the take-up lever.

3. A sewing-machine take-up mechanism, 50 comprising a rotary crank, a pin rotatably mounted on said crank and carrying an eccentrically-supported pivot, a take-up lever connected only at one end to said pivot and being bodily adjustable thereby in a direction 55 radially relative to the axis of said crank, and a link coöperating with said crank for controlling the movement of the take-up lever.

4. A sewing-machine take-up mechanism, 60 comprising a rotary crank-disk having an opening therein, a pin rotatably seated within said opening and carrying an eccentrically-supported pivot, a take-up lever connected at one end only with said pivot and being 65 bodily adjustable thereby in a direction radially relative to the axis of the said crank, and a pivoted link coöperating with said crank for controlling the movement of the take-up lever.

5. In a sewing-machine, the combination with a take-up mechanism comprising a rotary crank, an adjustable pivot carried by said crank, a clamping-screw located at the periphery of the crank for securing said pivot 75 in adjusted position, a take-up lever connected at one end to said pivot, and means coöperating with said crank for controlling the movement of said take-up lever, of the frame of the machine supporting and partially inclosing said take-up mechanism and having an opening in a position opposite the path of movement of said clamping-screw of the take-up mechanism, for the purpose set forth.

Signed at New York, in the county of New York and State of New York, this 8th day of April, A. D. 1904.

WILLIAM M. AMMERMAN.
